Paul Kircher
Williams, Bradbury
McClellan & Pierce, Atty's

UNITED STATES PATENT OFFICE.

PAUL KIRCHER, OF CHICAGO, ILLINOIS, ASSIGNOR TO MASSEY CONCRETE PRODUCTS CORPORATION, OF CHICAGO, ILLINOIS, A CORPORATION OF VIRGINIA.

REINFORCED-CONCRETE PIPE.

Original application filed July 14, 1921, Serial No. 484,556. Divided and this application filed March 20, 1922. Serial No. 545,056.

To all whom it may concern:

Be it known that I, PAUL KIRCHER, a citizen of the United States, and resident of Chicago, in the county of Cook and State 5 of Illinois, have invented a certain new and useful Improvement in Reenforced-Concrete Pipes, of which the following is a full, clear, concise, and exact description, reference being had to the accompanying drawings, 10 forming a part of this specification.

This invention relates to a reenforced concrete pipe, and particularly to concrete pipes suitable for use in railway culverts and for other purposes which require that the pipe 15 be capable of withstanding severe forces transmitted thereto in lines substantially at right angles to the longitudinal axis of the pipe.

It is the object of this invention to provide 20 a pipe which will comprise a minimum amount of concrete and reinforcing material in its construction but which, nevertheless, is capable of resisting the severe strains to which it may be subjected.

Prior to applicant's invention disclosed in 25 his application, Serial No. 484,556, filed July 14, 1921, of which the present application is a division, the most successful type of railway culvert pipes had been constructed in 30 accordance with the teachings of United States Patent Number 709,794. The present invention, as set forth in applicant's prior application, retains all the advantages of the above mentioned patent, and, in addition, affords important advantages not heretofore attained in the construction of concrete pipe of the type to which the present 35 invention relates.

The present invention will best be understood 40 from a detailed description taken in connection with the accompanying drawings, in which—

Figure 1 is a transverse section of a reenforced pipe embodying my invention;

Figure 2 is a longitudinal section through the pipe on the line 2—2 of Figure 1, and

Figure 3 is a transverse section, similar to Figure 1, but showing a slightly modified form of the invention.

Referring to the drawings, at 10 is shown 50 a concrete pipe which is substantially annular in cross section. Imbedded in the pipe is a reinforcing cage 11 which consists of a strip of woven wire material as wire net-

ting, the ends of which are caused to overlap and are preferably tied together to facilitate maintaining the cage in position in the pipe form. The cage 11 is elliptical in cross section and extends through the various regions of tension in the pipe. It is 55 well known that when a pipe, as shown in Figure 1, is subjected to vertical stresses, as when used as a railway culvert, regions of tension occur at the top and bottom adjacent to the inner surface of the pipe and at 60 the sides of the pipe adjacent to the outer surface thereof. Thus, it will be noted that the cage 11, as viewed in Figure 1, extends adjacent to the outer surface of the pipe 10 at the sides of the pipe and adjacent to the 65 inner surface of the pipe 10 at the top and bottom thereof.

In order to reduce the possibility of the cage 11 being torn out of the concrete at the 70 regions of tension where it is adjacent to the inner surface of the pipe, a pair of wire netting or wire fabric strips 12 and 13 are provided, which are co-extensive longitudinally with the cage 11 and are arranged substantially tangentially to and in engagement 75 with the cage at the point where it is nearest to the inner surface of the pipe.

The reinforcing strips 12 and 13 are preferably secured to the cage 11 by being tied thereto, preferably by wire, as indicated at 80 14 and 15. The lateral edges of the strips 12 and 13 extend from the regions of tension adjacent the inner surface of the pipe at the top and bottom outwardly into regions of 85 compression. The anchoring of the reinforcing strip edges in portions of the concrete removed from the regions of internal tension minimizes the possibility of the cage being pulled out of the concrete at the 90 regions of internal tension when the pipe is 95 forced to sustain a heavy load.

In Figure 3 is shown a modification of the arrangement shown in Figures 1 and 2. In this modification, the lateral edges of the reinforcing strips 12 and 13 are bent inwardly toward the cage 11 and are secured thereto as indicated at 16. Thus, the reinforcing strips are more firmly secured to the cage by being tied thereto at a greater 100 number of points.

While the wire netting reinforcing cage 105 shown in the present application is more particularly adapted as a means for reinforc-

ing concrete pipe of relatively small diameter, still it may be used advantageously in reinforcing pipes of larger diameter if the netting or screen employed is made of wires of sufficient size and strength.

Having thus described my invention, what I claim as new and desire to secure by Letters Patent of the United States is:

1. A reenforced pipe comprising a pipe body of initially plastic material, a substantially elliptical reinforcing cage imbedded in said pipe and having its opposite ends overlapped, and separate reinforcing tension members in said pipe adjacent and substantially tangential to said cage on opposite sides thereof.

2. In a pipe comprising a body formed of initially plastic material, a reinforcing cage imbedded in said pipe having its opposite ends overlapped, said cage being positioned adjacent to the outer surface of said pipe on opposite sides thereof and adjacent to the inner surface of said pipe at points between said opposite points, and separate reinforcing tension members adjacent and substantially tangential to said cage at the portions thereof which are adjacent to the inner surface of said pipe.

3. In a pipe comprising a body formed of initially plastic material, a reinforcing cage of woven wire fabric imbedded in said pipe having its opposite ends overlapped, said cage being positioned adjacent to the outer surface of said pipe at substantially diametrically opposite sides thereof and adjacent to the inner surface of said pipe at points between said opposite points, and separate reinforcing tension members substantially longitudinally co-extensive with said cage adjacent and tangential to said cage at the portions thereof which are adjacent to the inner surface of said pipe.

4. In a pipe comprising a body formed of initially plastic material, a reinforcing cage of woven wire fabric imbedded in said pipe having its opposite ends overlapped, said cage being positioned adjacent to the outer surface of said pipe at diametrically opposite sides thereof and adjacent to the inner surface of said pipe at points midway between said opposite points, and separate reinforcing members adjacent and tangential to said cage at the portions thereof which are adjacent to the inner surface of said pipe and extending outwardly from the cage to points adjacent to the outer surface of the pipe body.

5. As an article of manufacture, a pipe body of initially plastic material reenforced by a cage of woven wire fabric having its opposite ends overlapped, said cage being positioned adjacent to the outer surface of said pipe at diametrically opposite sides thereof and adjacent to the inner surface of said pipe at points between said opposite points, and

separate reinforcing members adjacent and tangential to said cage at the portions thereof which are adjacent to the inner surface of said pipe, the ends of said reinforcing members extending outside of the cage toward the outer surface of the pipe body.

6. An article of manufacture comprising a pipe body of initially plastic material, and a reinforcing cage imbedded in the pipe body and lying adjacent to the outer surface of the pipe at substantially diametrically opposite points and adjacent to the inner surface of the pipe at points intermediate said opposite points, said cage consisting of a single strip of woven wire fabric having its opposite ends overlapping, and tension members associated with those portions of the cage which lie adjacent to the inner surface of the pipe and extending outwardly from the cage to points adjacent to the outer surface of the pipe body.

7. A reenforced concrete pipe comprising a substantially circular pipe body of initially plastic material having imbedded therein a reinforcing cage consisting of a single strip of wire fabric having its opposite ends overlapped, said cage being positioned adjacent to the outer surface of said pipe at substantially diametrically opposite points and adjacent to the inner surface of said pipe at points substantially midway between said opposite points, and tension members associated with said cage and extending outwardly from those portions of the cage which lie adjacent to the inner surface of said pipe, said tension members lying substantially tangential to the cage, the outwardly extending portions of said tension members being provided with offsets which terminate near the outer surface of the cage.

8. A reenforced pipe comprising a pipe body of initially plastic material, a substantially elliptical reinforcing cage imbedded in said pipe having its opposite ends overlapped, and separate reinforcing tension members in said pipe adjacent and substantially tangential to said cage on opposite sides thereof, the edges of each of said tension members extending outwardly toward the outer surface of said pipe body and being provided with offsets which terminate adjacent to said cage.

9. A reenforced concrete pipe comprising a pipe body of initially plastic material, a reinforcing cage of woven wire fabric imbedded in said pipe having its opposite ends overlapped, said cage being positioned adjacent to the outer surface of said pipe on diametrically opposite sides thereof and adjacent to the inner surface of said pipe at points substantially midway between said opposite points, and separate reinforcing tension members adjacent and tangential to said cage at the portions thereof which are adjacent to the inner surface of said pipe,

said tension members extending outwardly from the cage to points adjacent to the outer surface of the pipe body and terminating adjacent to said cage.

- 5 10. A reenforced concrete pipe comprising a substantially circular pipe body of initially plastic material having imbedded therein an elliptical reinforcing cage formed of a single strip of woven wire fabric having its opposite ends overlapped, said cage passing adjacent to the outer surface of said pipe at substantially diametrically opposite points and adjacent to the inner surface of said pipe at points substantially midway between said opposite points, and rein-

forcing tension members associated with said cage and extending outwardly from those portions of the cage which lie adjacent to the inner surface of said pipe, said tension members lying in lines substantially 20 tangential to the cage, the outwardly extending portions of said tension members being rebent and terminating near the surface of said cage.

In witness whereof, I hereunto subscribe 25 my name this 17th day of March, 1922.

PAUL KIRCHER.
